Charles D. Gooding.

UNITED STATES PATENT OFFICE.

MABEL H. SLATER, OF NEW YORK, N. Y.

DOLL'S HEAD WITH MOVABLE EYES.

1,414,901.

Specification of Letters Patent.

Patented May 2, 1922.

Application filed February 28, 1921. Serial No. 448,329.

To all whom it may concern:

Be it known that I, MABEL H. SLATER, a citizen of the United States, residing at New York, in the county of New York and State 5 of New York, have invented new and useful Improvements in Dolls' Heads with Mov- able Eyes, of which the following is a speci- fication.

This invention relates to an improved 10 doll's head.

The object of the invention is to provide a doll's head which can be used as a receptacle for any desired articles, more particularly as 15 a receptacle for coins and thus constitute a toy bank.

The object of the invention is further to provide a doll's head in which the eyes are movable in grooves so as to assume different 20 positions relatively to each other and relatively to the nose of the face of the doll, whereby the head, upon being tipped, causes the eyes to roll in the grooves and assume different positions, making the same very 25 amusing and also requiring considerable skill to cause the eyes to assume various positions relatively to each other.

The invention also embodies a removable closure which can be used as a pen-wiper.

The principal novelty of the invention re- 30 sides in the construction whereby the eyes can be moved by tipping the head in different positions to assume different relative positions.

The invention consists in the combination 35 and arrangement of parts set forth in the following specification and particularly pointed out in the claims thereof.

Referring to the drawings:

Figure 1 is a front elevation of a doll's 40 head embodying my invention and particu- larly adapted to be used as a toy bank.

Fig. 2 is a transverse section of the same taken on the line 2—2, Figure 1.

Fig. 3 is an enlarged front elevation of 45 one of the eyes.

Fig. 4 is a detail sectional elevation taken on the line 4—4, Fig. 3.

Fig. 5 is a detail section taken on the line 5—5, Fig. 3.

50 Like numerals refer to like parts throughout the several views of the drawings.

In the drawings, 6 is a doll's head em- 55 bodying my invention. In the drawings this head is designed to imitate a Chinaman, but it is evident that, without departing from the spirit of the invention, it might imitate

any kind of a face. The head, as a whole, forms a container which may be used as a toy bank, 7 being the mouth through which coins 8 may be inserted into the interior of 60 the head. 9 is a closure adapted to be inserted in the opening 10 in the top of the head and to be removed when it is desired to take the coins out of the head. This closure is preferably made of bristles, so that 65 they can be used as a pen-wiper. 12 and 13 are the eyes of the doll consisting of upper lids 14 and 15 and lower lids 16 and 17 with slits 18 and 19 interposed between said upper and lower lids. A curvilinear groove 70 20 is provided adjacent to and at the rear of each of the slits 18 and 19 and a ball 21 is located in each of said grooves representing the eye-balls of the doll. These grooves are curvilinear in form and terminate in 75 pockets 22 and 23, said pockets being separated from each other by a cam-shaped partition 24, so that when the ball is located in either one of the pockets the head is tipped in order to cause the ball to roll in its 80 grooves over the cam-shaped partition 24 and into the pocket 24 and vice versa.

It will be noted by reference to Figs. 4 and 5 that the upper lid 14 and the lower lid 16 project forwardly and downwardly 85 beyond the vertical median plane A—A, the width of the slits 18 and 19 being less than the diameter of the ball 21, so that the ball cannot drop out through the slits.

In order to cause the eyes to assume dif- 90 ferent positions in their respective grooves, considerable skill is required, for instance, if it is desired to have both of the eyes in the ends of the grooves nearest the nose, the head has to be tipped and shaken in a cer- 95 tain way in order to get the eyes to assume these positions. The same is true if it is desired to have the eye-ball 21 enter the pocket 23 which is nearest the nose, while the other eye-ball is caused to enter the 100 pocket 22 which is farthest from the nose on the other side thereof. Sometimes it is possible by very careful tipping and manip- 105 ulation of the doll's head to cause the eyes to stop on the top of the V-shaped partition 24, thus giving the doll the appearance of rolling its eyes upwardly. In other cases where the eyes are both in the ends of the pockets nearest the nose, it gives the doll a cross-eyed expression. By properly han- 110 dling the doll's head, the eyes can also be caused to enter the pockets farthest removed

from the nose in which case the doll assumes a wall-eyed expression. Thus it will be seen that a great deal of amusement can be obtained and considerable skill acquired by 5 means of this toy bank.

I claim:

1. A doll's head having, in combination, a nose, a pair of eyes located on opposite sides of said nose, said head having elongated grooves terminating at their opposite ends in pockets, in which grooves said eyes are located and along which they are adapted to roll from one of said pockets to the other, whereby they may assume different 10 positions.
- 15 2. A doll's head having, in combination,

a nose, a pair of eyes located on opposite sides of said nose, said head having elongated grooves terminating at their opposite ends in pockets said pockets being separated 20 from each other by cam-shaped partitions, in which grooves said eyes are located and along which they are adapted to roll from one of said pockets to the other, whereby they may assume different positions. 25

In testimony whereof I have hereunto set my hand in presence of two subscribing witnesses.

MABEL H. SLATER.
